UNITED STATES PATENT OFFICE.

FELIX GOTTSCHALK, OF NEW YORK, N. Y.

TRANSMITTER-CASING.

1,045,967.

Specification of Letters Patent.

Patented Dec. 3, 1912.

Application filed February 12, 1912. Serial No. 677,112.

To all whom it may concern:

Be it known that I, FELIX GOTTSCHALK, a citizen of the United States, residing at New York, in the county of New York and 5 State of New York, have invented certain new and useful Improvements in Transmitter-Casings, of which the following is a specification, reference being had to the accompanying drawing.

10 This invention relates to telephone transmitters and particularly to an improved form of that part of the transmitter casing which supports the variable resistance cell, and consists of an arrangement whereby the 15 adjusting screw employed for holding the cell stem is protected from mechanical injury, or corrosion due to the presence of air or moisture. This is accomplished by providing an air and water-tight cover for the 20 screw and by other arrangements hereinafter described.

I further provide a terminal for the circuit connecting cord or wire, which is very secure mechanically and which is formed in 25 the same piece as the cell support, thereby eliminating all intervening connecting pieces between the cell and the terminal.

It is obvious that my invention can be used with transmitters of any well-known 30 construction, the result being that many small parts are eliminated and a more compact and efficient structure secured.

Figure 1 is a front view of a transmitter embodying this invention with several portions removed. Fig. 2, is a cross sectional view through the transmitter. Fig. 3, is a detail of the front plate of the transmitter, with a portion of same broken away to show its interior construction. Fig. 4, is a detail 40 of a means for connecting the diaphragm to the cell of the transmitter. Fig. 5, is a detail of the casing with a portion broken away. Fig. 6, is a detail of the terminal block, and, Fig. 7, is a detail of the diaphragm and its packing.

Like figures of reference denote the same parts wherever they are shown.

1 denotes the casing usually used in transmitters—especially those of the semi-water- 50 proof type.

2 is the usual sound receiving diaphragm which is often provided with the resilient packing 3.

4 is a front plate carrying the mouth- 55 piece, this front plate being secured to the

casing in any convenient manner. A small strip of metal 5 serves to form an electrical connection between the diaphragm and the casing by bridging across the resilient packing.

60 Heretofore it has been customary to carry the circuit from the front electrode of the usual cell 6 to an insulated terminal, conveniently mounted on the casing by means of a fine wire, which is a fruitful source of trouble. I obviate this by providing block 7 which is bored out to accommodate the stem 8 of the cell, and which is secured to the casing by screws 9, 10, 11 and 12 placed in bushings which insulate them from 7 in 70 any suitable manner. Packing 13 is provided for sealing the joint between 7 and 1, thereby inclosing the cell in a tight chamber.

To further provide against the ingress of moisture and to prevent tampering with the 75 cell adjustment, I provide the screw 14 having the packing 15, which closes the hole 16, in which is placed the usual adjusting screw 17. Block 7 also carries a suitable terminal 18 for the circuit connection 19.

80 The circuit through the instrument is from the casing to the diaphragm through the piece 5, then through resistance cell 6 to block 7 and circuit connection 19, all fine wires or loose connections being avoided.

85 I claim:

1. In a telephone transmitter, an apertured front plate, a diaphragm positioned back of said front plate, a cell support back of said diaphragm, a resistance cell in said support, an adjusting screw for said cell, an aperture in said cell support for said adjusting screw and means comprising a screw and water tight packing therefor for closing said aperture and covering said adjusting 95 screw.

2. In a telephone transmitter, a casing having an apertured front, a diaphragm in said casing, a cell support positioned at the reverse side of the diaphragm from the 100 apertured front of said casing, but carried thereby and insulated therefrom, a resistance cell carried by said support, an aperture in said cell support communicating with the stem of said cell, adjusting means 105 for said stem in said aperture, a screw in said aperture above said adjusting means and water tight packing around said screw.

3. In a telephone transmitter, a casing having a rearwardly projecting apertured 110

flange, a cell support mounted on and insulated from said flange, a transmitter cell carried by said support and projecting into said apertured casing, a diaphragm, means connecting said diaphragm to said cell, resilient packing between said diaphragm and said casing, an adjusting screw in said support, and means for covering said adjusting screw comprising a screw having water

tight packing surrounding its head, and a terminal carried by said support.

In testimony whereof I hereunto affix my signature in the presence of two witnesses.

FELIX GOTTSCHALK.
